ABSTRACT

Apparatus for containing the blades of an electrical plug, especially where the plug includes a ground blade. A highly reliable ground is provided for the non-conducting metal structure of the plug by permanently connecting the ground blade thereto. The wiring terminal on the ground blade is externally disposed on the plug to facilitate verification of the ground wire connection to the plug. To avoid the safety hazard otherwise presented thereby, the wiring terminals on the power blades are structurally enveloped within the plug.

PATENTED SEP 10 1974

3,835,437

GROUNDING PLUG

BACKGROUND OF THE INVENTION

The present invention relates to container apparatus for a grounded plug and particularly to such apparatus for enclosing the wiring terminals on the power blades within the structure of the plug while permanently affixing the ground blade electrically to the non-conducting metal structure of the plug. Hitherto, many different devices have been used to contain the terminal blades of a grounded plug. Generally, all grounded plugs provided for the electrical cord to enter from the rear and contain power and ground blades which protrude from the front. Existing codes require that all non-conducting metal structure on grounded plugs, such as cord clamps, must be electrically connected to the ground blade.

In some plugs, the wiring terminals on all blades are accessible through an opening in the front (hereinafter open front type), while in other plugs such accessibility is only attained after removing a blade holder to which all blades are secured (hereinafter dead-front type). The open front plugs are advantageous because the ground blade is permanently affixed electrically to the non-conducting metal structure of the plug. Also, the integrity of the ground wire connection to the plug may be verified without disassembling the plug. These open front plugs, however, present a safety hazard in some applications because the wiring terminals on the power blades are not completely enclosed by the structure of the plug. The dead-front plugs are advantageous because the wiring terminals on the power blades are completely enclosed by the structure of the plug. However, the removable nature of the blade holder makes it necessary to incorporate a disconnecting electrical interface between the ground blade and the non-conducting metal structure of the plug. Also, to verify integrity of the ground wire connection in a dead-front plug, the blade holder must be detached from the plug.

SUMMARY OF THE INVENTION

It is, therefore, a general object of the present invention to provide a grounded plug having a container apparatus which minimizes and obviates the disadvantages of the prior art.

It is a specific object of the present invention to provide a grounded plug having a container apparatus which structurally encloses the wiring terminals on the power blades while permanently connecting the ground blade electrically to the non-conducting metal structure of the plug.

It is a more specific object of the present invention to provide a grounded plug having a container apparatus in which the integrity of the ground wire connection may be verified without disassembly of the plug.

These objects are accomplished according to the present invention by partitioning a plug body into an open compartment and an elevated surface. Power blades having wiring terminals are secured in an insulated holder which is retained to the plug body with the wiring terminals disposed in the open compartment. The power blades extend externally from the holder which is configured to close off the open compartment. A ground blade is permanently connected electrically to the non-conducting metal structure of the plug and

is disposed within the plug body to extend from the elevated surface. A wiring terminal on the ground blade is disposed to be externally exposed on the plug.

BRIEF DESCRIPTION OF THE DRAWING

The manner in which these and other objects of the invention are achieved will be best understood by reference to the following description, the appended claims, and the attached drawing wherein:

10 FIG. 1 is a perspective view of a grounded plug incorporating the container apparatus of this invention;

15 FIG. 2 is an exploded view thereof without the cable and with portions of the plug body cut away to illustrate the separate mounting provisions utilized for the power blades and the ground blade;

20 FIG. 3 is a perspective view of the blade holder to which the power blades are secured;

25 FIG. 4 is a front elevational view of the grounded plug illustrating the external connection of the ground wire to the wiring terminal on the ground blade;

30 FIG. 5 is a sectional view thereof taken substantially along line 5—5 of FIG. 4 to illustrate the structural enclosure provided for the wiring terminals of the power blades and the permanent electrical connection provided between the ground blade and the binding plate; and

35 FIG. 6 is a sectional view thereof taken substantially along line 6—6 of FIG. 5 to illustrate the interior construction of the plug.

DESCRIPTION OF THE PREFERRED EMBODIMENT

Turning now to the drawing, and more particularly to FIG. 1, there is illustrated a grounded plug 10 into which the improvements of this invention have been incorporated. Generally, the grounded plug 10 is used to connect the wires of an electrical cord 12 to a source of power from an outlet (not shown). The grounded plug 10 includes a plug body 14 from which two power blades 16 and a ground blade 18 extend. A ground wire 20 of the cord 12 passes from the interior of the plug 10 through a conduit means and connects to the ground blade 18. At its other end, the ground wire 20 is usually connected to the housing of the electrical equipment utilizing the power, to thereby eliminate the safety hazard presented when short circuit conditions exist in the equipment. To relieve stress on the electrical connections within the plug 10, a conventional cord clamp 22 is secured to the plug body 14 by suitable means such as discussed below. Typically, the cord clamp 22 has a pair of jaw members 23 which are interconnected by screws 24.

40 As illustrated in FIG. 2, the plug body 14 is generally cylindrical in shape and is interiorly partitioned to provide an elevated surface 25 in a contiguous location to an open compartment 26. The ground blade 18 is disposed to extend from the elevated surface 25 and is permanently fixed to the plug 10. The power blades 16 are secured within a blade holder 28 which is configured for insertion into the plug body 14 over the open compartment 26. Support surfaces 30, 32, 34 and a gripping lip 36 are disposed within the plug body 14 to align and retain the blade holder 28 upon full insertion, as shown in FIG. 4. Any suitable means may be utilized to secure the blade holder 28 to the plug body 14, such as a binding screw 38.

Any suitable terminal means for connecting to wires can be utilized on either the ground blade 18 or the power blades 16. The terminal means utilized on the ground blade 18 is a terminal screw 40 threaded into a mounting flange 42 as shown in FIG. 4. The mounting flange 42 abuts against the elevated surface 25 and therefore, the elevated surface 25 and its supporting structure within the plug body 14 must be relieved to accommodate the length of the screw 40. The terminal means on each power blade 16 is a screw 44 threaded into a lug head 46 which is an integrally formed portion of the power blade 16 as shown in FIGS. 2 - 6.

The plug body 14 is made from an electrically insulating, elastomeric material and has a particular interior configuration. In addition to the open compartment 26, the elevated surface 25, the support surfaces 30, 32, 34, and the gripping lip 36 previously discussed, the plug body 14 contains a rear entrance 48 as illustrated in FIG. 5. The cord 12 passes into the open compartment 26 through the rear entrance 48 and contains power conducting wires 49 in addition to the ground wire 20. Perpendicularly across the rear entrance 48, the exterior of the plug body 14 is recessed to accommodate mounting ears 50 on the jaw members 23 of the cord clamp 22, which are retained to the plug body 14 under an annular binding plate 52.

The cord clamp 22 and binding plate 52 are made of metal but they are non-conducting and only a structural part of the plug 10. Many safety codes require that the non-conducting metal structure on grounded plugs 10 must be electrically connected to the ground blade 18. When complying with such codes, it is most desirable to permanently affix the ground blade 18 in the plug 10, which thereby avoids the need of a detachable ground connection. Any suitable fastening means can be utilized to permanently affix and electrically connect the ground blade 18 to the plug 10. A most convenient arrangement is to secure the ground blade 18 to the binding plate 52 with a rivet 54 extending through a load bearing eyelet 56 which is disposed through the plug body 14, as shown in FIG. 5. The binding screw 38 securing the blade holder 28 to the plug body 14 also threads through and secures to the binding plate 52.

Detailed construction of the blade holder 28 is illustrated in FIGS. 2 - 6, where each power blade 16 extends perpendicularly through a partially cylindrical bulkhead 58 of an insulated base 60. A T web 62 extends perpendicularly back from the bulkhead 58, as shown in FIGS. 2 - 3, and has a leg portion 64 and a cross portion 66. The lug heads 46 and screws 44 on the power blades 16 are separated by the leg portion 64. The top surface of the cross portion 66 is configured to have a protruding fin 68 and a groove 70 which runs parallel to the leg portion 64. A standoff column 72 also extends perpendicularly back from the bulkhead 58 and traverses along the bottom of the leg portion 64. An aperture 74 extends through both the bulkhead 58 and the standoff column 72 and is counterbored from the external face of the bulkhead 58. A raised lip 76 extends around the cylindrical surface on the side of the bulkhead 58.

Interassembly of the plug body 14 and the blade holder 28 is accomplished by directing the standoff column 72 on the blade holder 28 between the support surfaces 32 and 34 within the plug body 14. The blade holder 28 is then forced into the plug body 14 until the

fin 68 abuts against the support surface 30 and the bulkhead 58 abuts against both support surfaces 32 and 34. When the blade holder 28 is fully inserted into the plug body 14, the gripping lip 36 on the plug body 14 snaps over the raised lip 76 on the blade holder 28 to provide limited retention thereto. Thereafter, the binding screw 38 is inserted into aperture 74 and tightened to secure the blade holder 28 to the plug 10. The terminal means on the power blades 16 are then structurally enveloped by the plug 10.

To connect the cord 12 to the plug 10, the binding screw 38 is loosened and the blade holder 28 is removed from the plug body 14. The screws 24 are manipulated to open the jaw members 23 of the cord clamp 22. One end of the cord 12 is then directed through the rear entrance 48 and open compartment 26 of the plug body 14, until the plug body 14 is disposed well back from the end of the cord 12. The jacket on the cord 12 is then removed for an appropriate length to expose the wires 20 and 49. The insulation is then stripped from the power conducting wires 49 which are then connected to the appropriate power blades 16 on the blade holder 28. The ground wire 20 is disposed within the groove 70 on the blade holder 28 which serves as the conduit means from the interior of the assembled plug 10. The cord 12 is directed back through the compartment 26 and rear entrance 48 of the plug body 14 until the blade holder 28 is joined to the plug body 14 in the manner previously described. After this jointure the binding screw 38 is tightened to secure the blade holder 28 to the plug body 14 with the ground wire 20 extending from the plug 10 in a similar direction to the blades 16 and 18. The ground wire 20 is then stripped of insulation and connected to the ground blade 18 under the externally disposed terminal screw 40.

It should be readily appreciated by those skilled in this art that the plug container apparatus embodied by this invention structurally envelops the wiring terminals on the power blades to avoid short circuits, while reliably affixing the ground blade permanently to the non-conducting metal structure of the plug. Furthermore, the wiring terminal on the ground blade is disposed externally on the plug, which permits the integrity of the ground connection to be verified without disassembling the plug.

It should be understood that the present disclosure has been made only by way of example and that numerous changes in details of construction and the combinations or arrangements of parts may be resorted to without departing from the true spirit and scope of the invention and therefore, the present disclosure should be construed as illustrative rather than limiting.

What we claim is:

1. An electrical plug comprising:
a blade holder, said blade holder having power blades disposed therethrough and supported thereby, said power blades including terminal means for connecting to electrical wires;
a plug body, said plug body including non-conducting metal structure and being configured to detachably secure said blade holder with said terminal means structurally enclosed therein; and
a ground blade, said ground blade being permanently affixed to said plug body in electrical continuity with said non-conducting metal structure.

2. The electrical plug of claim 1 wherein conduit means for passing a ground wire from within said plug body is included on said electrical plug and wherein said ground blade includes terminal means for connecting to electrical wires, said ground blade terminal means being externally accessible on said electrical plug.

3. The electrical plug of claim 2 wherein said conduit means includes a groove disposed on said blade holder.

4. The electrical plug of claim 1 wherein said terminal means includes a screw threading into each said power blade.

5. The electrical plug of claim 1 wherein said plug body includes an open compartment and an elevated surface contiguous to said open compartment, said terminal means on said power blades being disposed within said compartment and said ground blade being disposed to extend from said elevated surface.

6. The electrical plug of claim 5 wherein said blade holder is configured to close off said open compartment.

7. The electrical plug of claim 1 wherein said non-conducting metal structure includes a binding plate, said ground blade being secured to said plug body by fastening means for attaching to said binding plate.

8. The electrical plug of claim 7 wherein said fastening means includes a rivet.

9. The electrical plug of claim 1 wherein conduit means for passing a ground wire from within said plug body is included on said electrical plug and said ground blade includes terminal means for connecting to electrical wires, said ground blade terminal means being externally accessible on said electrical plug; wherein said plug body includes an open compartment and an elevated surface contiguous to said open compartment and said non-conducting metal structure thereof includes a binding plate, said power blade terminal means being disposed within said compartment, said ground blade being disposed to extend from said elevated surface and being secured to said plug body by fastening means for attaching to said binding plate; and wherein said blade holder is configured to close off said open compartment.

10. The electrical plug of claim 9 wherein said power blade terminal means and said ground blade terminal means include screws threading into said blades; wherein said conduit means includes a groove disposed on said blade holder; and wherein said fastening means includes a rivet.
